STEP-BY-STEP SWITCH

Gerald J. Barry, Philadelphia, Pa., assignor, by
mesne assignments, to Philco Radio and Tele-
vision Corporation, Philadelphia, Pa., a cor-
poration of Delaware

Application June 3, 1939, Serial No. 277,273

7 Claims. (Cl. 74—155)

This invention relates to positioning devices for actuating an element or elements to certain selectable positions and, more particularly, the invention relates to a novel step-by-step mechanism adapted to respond to control impulses and to position the controlled elements in a novel manner.

In the copending application of Milton L. Thompson, Serial No. 220,356, filed July 20, 1938, and the copending application of David Grimes and Elmer O. Thompson, Serial No. 220,366, filed July 20, 1938, there are disclosed and claimed certain remote control systems for radio receivers wherein the control of a radio receiver is effected by means of controlling impulses which actuate a stepping mechanism to effect volume control, station selection, and "off and on" actuation of the energizing switch at the receiver, as well as other desirable functions with which the present invention is not directly concerned. In those control systems, the controlling impulses are sent by means of a dial-controlled impulse generator which generates the controlling impulses under control of a finger-operated dial similar to a telephone dial. For reasons which are not important here, two of the finger positions of the dial are reserved for volume control impulses, and one of these finger positions is effective to cause generation of a pulse of fixed short duration followed by a control impulse of controllable duration, while the other of these finger positions is effective to cause generation of two pulses of fixed short duration followed by an impulse of controllable duration. One of the control impulse trains thus generated is adapted to effect a volume level change at the receiver in one direction, for example, an increase in the volume level; while the other impulse train is adapted to effect a volume level change in the opposite direction, for example a decrease in the volume level. The subsequent finger positions of the dial are reserved for the control of station-selecting means at the receiver, the particular station selected in any instance being determined by the number of successive impulses of fixed short duration generated by the impulse-generating means under control of the dial. For example, if a train consisting of four successive short impulses is generated, a certain station will be selected at the radio receiver, while if a train of five impulses is generated, another station will be selected at the receiver, etc.

In the said copending Grimes and Thompson application, there is further disclosed a novel stepping mechanism comprising two shafts, one

adapted to control a step-by-step switch which effects volume control changes and also mutes or silences the receiver during station selection, while the other shaft is adapted to control station-selecting switches. The two shafts are rotatable relative to one another but are interconnected in a novel manner to effect rotation of the second shaft when the first shaft is operating through a portion of its operating range. In other words, the first shaft has a certain operating range, while the second shaft has a smaller operating range that is coextensive with a portion of the operating range of the first shaft. The first shaft is operated in a step-by-step manner by means of the controlling impulses and it rotates free of the second shaft in response to the volume control impulses above mentioned; but, when a train of station-selecting impulses is generated, the second shaft is operated in unison with the first shaft to effect station selection at the same time that the receiver is muted or silenced by the operation of the first shaft. It is further provided that the first shaft returns to its home position following the last control impulse, while the second shaft is maintained in the position to which it is actuated to thus maintain the desired tuning of the receiver, and when the first shaft is again actuated in response to a subsequent train of station-selecting impulses, the second shaft is returned to its home position and is again operated in unison with the first shaft. The homing of the first shaft is controlled by a homing relay or magnet.

In the copending application of Francis 35 Richardson, Serial No. 220,381, filed July 20, 1938, there is disclosed and claimed a novel step-by-step positioning device wherein the homing action is controlled by a novel time-delay mechanism which eliminates the necessity of providing a homing relay and which renders the device responsive to the frequency of occurrence of successive control impulses insofar as the homing action is concerned.

By the present invention, there is provided a 45 novel stepping mechanism which is generally similar to that of the said Grimes and Thompson application and which is adapted to control the positions of two rotatable elements and associated switches in the manner above-mentioned but which embodies a simple and novel time-delay mechanism as an improvement over that of the said Richardson application. As in the Richardson device, the homing action of the present device is controlled by the time-delay means so that the homing action is effected ac-

cording to the frequency of occurrence of the received impulses. It will be understood, therefore, that this invention provides a novel stepping mechanism which may be used in the system of the said copending Grimes and Thompson application and which is in the nature of an improvement over the several stepping mechanisms above mentioned.

The principal object of the present invention, therefore, is to provide a novel stepping mechanism which is adapted to control the positioning of two rotatable elements, one having a certain range of movement and the other having a range of movement coextensive with a portion of the operating range of the first element, and the two elements being operated in unison over their co-extensive ranges.

Another object of the invention is to provide a device of this character embodying novel means responsive to the frequency of control impulses for governing the homing action of the device.

Still another object of the invention is to provide a novel positioning device for controlling the position of a movable element in response to received control impulse trains, which device embodies novel means for controlling the homing action thereof according to the frequency of occurrence of the successive impulses.

A further object of the invention is to provide in a device of the stated character novel time delay means for effecting homing action after a predetermined interval following a control impulse, the said time delay means comprising a device wherein the delay action is obtained by the frictional engagement of a flexible cord with a stationary drum.

A still further object of the invention is to provide in a device of the stated character novel means for preventing the second element from getting out of step with the first element during tandem operation of the two elements.

Other objects and features of the invention will be apparent hereinafter.

In the drawings:

Figure 1 is an elevational view of the complete device, showing both primary and secondary switch sections;

Fig. 2 is an elevational view of the operating mechanism;

Fig. 3 is a fragmentary sectional view taken along line 3—3 of Fig. 2;

Fig. 4 is a detailed sectional view taken along line 4—4 of Fig. 3;

Fig. 4a is a fragmentary perspective view of the ratchet structure in inverted position;

Fig. 5 is a sectional view taken along line 5—5 of Fig. 2;

Fig. 6 is a detailed sectional view taken along line 6—6 of Fig. 5;

Fig. 7 is a face view of the operating mechanism showing clearly the primary switch section of the device;

Fig. 8 is a detailed illustration of the novel time delay mechanism provided by the invention; and

Fig. 9 is a plan view of the device.

Referring to the several views of the drawings, and particularly to Fig. 1, the device is assembled on a U-shaped base or support 1 which is adapted to be secured to mounting brackets 2 which in turn may be secured to a supporting panel 3. The operating mechanism of the device is positioned within the U-shaped support 1, and is constructed as follows. An electromechanical relay 4 is mounted on a bracket 5 which

is secured to one of the upright sides of support 1, as clearly shown in Figs. 1 and 2. The relay 4, which constitutes the stepping relay, comprises a coil winding 6 and an armature 7, the latter being pivotally secured at 8 to the supporting bracket 5 (see Fig. 5). A spring 9 serves to maintain the armature in its normal inoperative position and moves the armature to that position whenever the relay is deenergized. In operation, current impulses are supplied to winding 6 through leads shown in Fig. 1, and upon receiving a control impulse, the electromagnet of the relay attracts the armature 7 against the action of spring 9, as will be well understood, the armature pivoting about point 8 so that its lower end moves in a small arc. The armature carries an operating arm 10, the lower end of which serves as a stepping pawl. The arm 10 extends through a slot in the supporting base 1 (see Fig. 7) and moves in the slot whenever the armature 7 is actuated. An edge of the slot serves as a stop to limit the movement of the armature under the influence of spring 9.

As shown clearly in Fig. 3, the base 1 carries a stationary stud or pin 11 which supports the rotatable elements whose movements it is desired to control, as will be described presently. The stud or pin 11 is supported by a stationary collar or sleeve 12, permanently secured to base 1, carrying a set screw 13 which engages the stud, as illustrated. A primary ratchet wheel 14 is carried by sleeve 18 which is rotatably mounted on the stud 11, and is urged to a normal or home position by means of a coil spring 15, one end of which is anchored to the primary ratchet at 16, while the other end of the spring is anchored to the sleeve 12 at 17. Thus, the spring 15 resists rotary movement of ratchet 14, and returns the ratchet to its home position whenever the ratchet is released after actuation thereof. The stepping pawl 10 operates ratchet 14, as described further hereinafter. A switch arm 19 is carried by sleeve 18 and forms part of the primary switch section of the device.

The lower end of sleeve 18 is provided with diametrically opposed recesses 20 (see Fig. 4) which serve to seat the nose portions 21 on arms 22 of a cam member 23 partially encircling the lower end of the sleeve. A coil spring 24 surrounding sleeve 18 has one end anchored to the ratchet 14 at 25, while the other end of spring 24 is anchored to the cam member 23 at 26. Thus, the cam member 23 is resiliently carried by sleeve 18 and rotates therewith. The cam portion 27 serves a purpose which will be explained presently.

A secondary ratchet 28 is carried by a collar or sleeve 29 which is rotatably mounted on the lower end of stud 11, as shown clearly in Fig. 3. The ratchet 28 carries an extending arm 30 (see Fig. 1) which actuates a rotatable arm 31 on a shaft 32 rotatably mounted in the bearing structure 33 carried by the supporting panel 3. At its lower end the rotatable shaft 32 carries switch arms 34 and 35 which are arranged to engage successive arcuately spaced stationary contacts 36 and 37, respectively, carried by an insulating support 38, which in turn is suspended from panel 3 by means of supports 39. The rotatable arms 34 and 35 whose positions are thus controlled by the secondary ratchet 28, together with the stationary contacts, constitute the second switch section of the device.

Referring now to Fig. 7, the switch arm 19 is arranged to engage successively a plurality of

spaced stationary contact elements 40 in response to stepping movement of the primary ratchet 14 through the medium of the stepping relay. Actuation of the switch arm 19 beyond the contacts 40 causes the arm to engage the arcuate stationary contact 41. In the specific application of the device to the control of a radio receiver, according to the method disclosed in the above-mentioned applications, the engagement of switch arm 19 with contacts 40 serves to control the volume of the radio receiver, while the engagement of the arm with the arcuate contact 41 serves to mute the radio receiver during station selection by the second switch section comprising contacts 34 to 31. However, the present invention is not concerned with the specific use to which the device may be applied, and its application to the control of a radio receiver is mentioned herein merely to illustrate one use of which the device is capable.

The arm 30 and its associated ratchet 28 are urged to the normal or home position, by a spring 42 (see Fig. 7) one end of which is secured to arm 30 at 43, while the other end of the spring is secured to a lug 44 on the support 1. In the home position of arm 30, the arm abuts against stop 30a carried by support 1. A pawl 45 serves as a holding pawl for ratchet 28 so as to maintain the arm 30 in any position to which it is actuated. The pawl 45 is resiliently carried by a leaf spring 46 which is secured to a bracket 47 mounted on support 1. On rotation of the ratchet 14, the pawl 45 is released by the cam member 23 simultaneously with engagement of arm 19 with the arcuate contact 41, thus, permitting the arm 30 and ratchet 28 to be homed by spring 42 preparatory to the station selection operation. Ratchet 28 carries a pin 48 (Fig. 1) which is engageable by a depending pin 49 on ratchet 14. The ratchet 14 serves to operate the ratchet 28 through the engagement of the two pins. This operation will be more fully described later.

As mentioned above, the lower end of arm 10 is formed so as to function as a stepping pawl which engages the primary ratchet 14. A spring 50 (see Figs. 2 and 7) has one end attached to the stepping pawl and has its other end anchored to support 1 at 51, so that this spring helps to maintain the pawl against the guide slot so as to properly engage the ratchet 14 upon the operation of the armature 7. A holding pawl 52 (Figs. 7 and 8) for the ratchet 14 is pivotally secured at 53 to support 1. A spring 54 has one end connected to the holding pawl at 55, while the other end of the spring is anchored to support 1. This spring urges the pawl 52 into engagement with ratchet 14, as may be clearly seen in Fig. 8, but the pawl is normally held out of engagement with the ratchet by means to be described presently. When the holding pawl 52 is permitted to engage ratchet 14, however, it serves to maintain the ratchet in any position to which it is actuated by the stepping pawl 10. As control impulses are supplied to the stepping relay, the stepping pawl 10 operates the primary ratchet 14 in step-by-step fashion, and the holding pawl 52 serves to maintain the ratchet 14 in the successive positions against the action of the homing spring 15.

One feature of the present invention resides in the provision of novel time delay means for controlling the operation of the holding pawl 52 so as to permit homing of ratchet 14 after a predetermined time interval following a control impulse. The details of the time delay device may

be clearly understood by referring particularly to Figs. 8 and 9. Above the horizontal portion of support 1, there is pivotally mounted a member 56 (see Fig. 9) whose pivot 57 is mounted on bracket 58 carried by support 1. The member 56 comprises an arm 59 having a hooked end 60 engageable by arm 10. The member 56 also has formed thereon an integral extension 61 which passes normally through an opening in support 1 and engages the holding pawl 52, as shown in Figs. 7, 8, and 9. A relatively heavy spring 62 has one end secured to the pivoted member 56 at 63 and has its other end anchored to a lug 64 on support 1. The spring 62 urges the pivoted member 56 in a direction to cause the pivoted member to move the holding pawl 52 out of engagement with ratchet 14, as shown in Fig. 8. Since the spring 62 exerts a greater force on the holding pawl 52 than the force exerted thereon by the spring 54, the pawl is normally held out of engagement with ratchet 14 against the action of its associated spring 54. Whenever the stepping pawl 10 is actuated, however, the member 56 is moved thereby against the action of spring 62 in such manner as to expand the same, thereby releasing the holding pawl 52 and permitting spring 54 to move the pawl into engagement with ratchet 14.

A stationary drum 65 is mounted upon support 1 and a flexible cord 66 is wound about the drum, there being sufficient turns of the cord upon the drum to provide the required friction grip between said elements. One end of the flexible cord is secured to member 56 at 67, while the other end of the cord is attached at 68 to an end of a relatively weak spring 69, the opposite end of which is secured at 70 to a bracket 71 carried by support 1. Normally, the cord is taut on the drum, being so held by the springs 62 and 69. When the member 56 is moved by the stepping pawl against the action of spring 62, as above mentioned, a certain amount of slack of the cord is provided which is immediately taken up by spring 69. Further, the holding pawl 52 is permitted to engage ratchet 14, as above described. Following each control impulse, the stepping pawl 10 returns to its normal position, thus releasing the member 56; and as a result, the heavy spring 62 tends to return member 56 to its normal position, but the frictional engagement of the cord 66 with drum 65 imposes a frictional drag upon the return movement of member 56, thus providing a time delay in the return of the member 56. If a succeeding control pulse is applied in proper sequence, the member 56 is prevented from returning to its normal position and the holding pawl 52 is permitted to continue its engagement with ratchet 14. However, if a control impulse is not received within the time delay period provided by the mechanism, the member 56 is returned to its normal position, causing the holding pawl 52 to be disengaged from ratchet 14 and thus permitting homing of the ratchet. It will be seen, therefore, that after a properly timed series of impulses has been applied to the device, the homing action will take place after a predetermined time interval following the last control impulse. It will be seen further that the occurrence of the homing action is dependent upon the frequency of occurrence of the successive control impulses, so that the device operates properly only in response to properly timed control impulses.

It will be apparent that the time delay action provided by the mechanism just described will

depend upon the design and adjustment of the elements constituting the said device. As shown in Fig. 6, the drum 65 may be eccentrically mounted upon a pin or stud 72 adjustably carried by means of a collar 73 and set screw 74. By rotating the pin 72 to a desired position, the position of the drum 65 may be adjusted to vary the action of the time delay mechanism, as will be readily understood.

Considering now the operation of the complete device, let it be assumed that both of the ratchets 14 and 28 are in home position, as shown in Fig. 7. Upon the application of a series of control impulses to the stepping relay, the stepping pawl 10 is actuated to step ratchet 14, thereby moving the contact arm 19 over its associated stationary contacts. At the same time, the stepping pawl 10 actuates the pivoted member 56 to permit the holding pawl 52 to engage the ratchet, as above described. During the application of properly timed successive control impulses, the holding pawl 52 is maintained in engagement with the ratchet, and prevents homing action, as described above. The cooperative pins 48 and 49 are so arranged that the pin 49 engages pin 48 simultaneously with the engagement of contact arm 19 with the arcuate contact 41. Consequently, the second ratchet 28 is rotated by the first ratchet through the medium of the two pins. The holding pawl 45, for the secondary ratchet, maintains the ratchet in the successive positions to which it is thus actuated. Consequently, the second switch section, comprising contacts 34 to 37, is maintained in the successive positions to which it is actuated. Following the cessation of the control impulses, the ratchet 28 is maintained in the last position to which it has been actuated, while the ratchet 14 is homed after a predetermined interval, as above described. Thus, the second switch section is maintained in a selected position, determined by the number of impulses, while the first switch section of the device is returned to normal or home position.

It will be understood, of course, that if the number of control impulses is not such as to move the contact arm 19 beyond the contacts 40, the ratchet 28 and the switch section controlled thereby will not be operated. Such action might obtain, for example, when the contacts 40 are employed to control the volume of a radio receiver, as above mentioned, and where the device is actuated to vary the volume of the receiver but not to effect a station selection.

Assuming that the device has been operated, as above described, to move the second switch section to a selected position, when it is desired to select a different position, a different series of impulses will be applied to the device. Remembering that the second ratchet 28 has been maintained in the position to which it was last actuated, the control impulses will affect operation of ratchet 14 and its switch arm 19 as above described. It will be remembered also that the cam member 23 is rotated by ratchet 14, and this cam member is so arranged that it engages pawl 45 just prior to the engagement of arm 19 with the arcuate contact 41. As may be seen from Fig. 7, the cam portion 27 deflects the resiliently mounted pawl 45 sufficiently to disengage the pawl from ratchet 28, thus permitting homing of the ratchet 28 and the second switch section under the influence of spring 42. Continued stepping rotation of ratchet 14 causes the pawl 45 to ride off the cam portion 27, permitting the pawl to again engage ratchet 28. At the same time, the

5 pins 48 and 49 engage one another, thus effecting stepping action of ratchet 28 from its home position, as above described. When the control impulses cease, the ratchet 14 is homed but the second ratchet 28 is held by pawl 45. During homing of ratchet 14 the cam 23 is deflected under pawl 45 by the curved end 27 (see Fig. 4a) so that the cam is unable to disengage pawl 45 from ratchet 28.

10 It will be seen, therefore, that the first ratchet 14 is operable over a predetermined range, while the second ratchet 28 is operable over a range which is coincident with a portion of the operating range of the first ratchet. Further, the 15 secondary ratchet is homed from any position to which it may have been actuated, preparatory to tandem movement of the two ratchets through the medium of the cooperating pins 48 and 49.

As above described, the novel time delay mechanism which controls the homing action of the primary ratchet is extremely simple in construction and operation, and yet operates efficiently to serve its intended purpose.

20 In addition to the principal switch sections of the device above described, there may be provided an auxiliary switch 75 (see Fig. 7), the spring arms of which tend to close the switch, but are held open during a predetermined portion of the operating cycle by a pivoted toggle member 76, one end of which acts as a cam, while the other end is bifurcated to accommodate pin 77 carried by ratchet 14. At a predetermined point in the operation of ratchet 14, this toggle mechanism operates to release switch 75, permitting it to close. This switch may be employed for any desired purpose with which the present invention is not concerned. The pin 77 may serve additionally to fix the home position of ratchet 14 by abutting against a fixed stop 77a on support 1.

25 Due to the rapidity with which such a device operates, it has been found that the second ratchet 28 tends to get out of step with the first ratchet. The momentum acquired by the second ratchet from the rapidly occurring successive impulses sometimes causes the second ratchet to advance more than a single step, thus causing the second switching section to move beyond the desired position. Obviously, when the device is used to control a radio receiver, such undesirable action may cause the selection of a station other than the one desired.

30 One form of device for eliminating this undesired action is disclosed and claimed in a co-pending application of Elmer O. Thompson, Serial No. 277,270, filed June 3, 1939, now Patent No. 2,206,926, granted July 9, 1940. A further feature of the present invention resides in the provision of other novel means for maintaining the desired relation between the primary and secondary ratchets. As shown in Fig. 7, there is provided an auxiliary pawl 78 which is pivotally mounted at 79 on the support 1, and is arranged for engagement with the second ratchet 28. A light spring 80 is arranged to urge the pawl 78 toward the associated ratchet. On the pawl, however, there is provided an extending lug 81 (see Fig. 2) which engages the back of the stepping pawl 10. When the stepping pawl is in normal inoperative position, it holds the pawl 78 out of engagement with the ratchet 28. Upon each actuation of the stepping pawl 10, however, the pawl 78 follows the stepping pawl under the influence of spring 80, and the elements are so arranged that the nose of pawl 78 engages

ratchet 28 immediately following the stepping action effected by the stepping pawl. Thus, each step-by-step movement by the ratchet 28 is accompanied by engagement of pawl 78 with the ratchet, thus preventing the latter from moving beyond a single step. Thus, there is provided a simple device in the form of the auxiliary pawl 78 whose action is controlled by the stepping pawl in a manner to prevent excess movement of the secondary ratchet. By the provision of this simple device, the above-mentioned undesirable tendency is eliminated.

From the illustration of the drawings and from the above detailed description, it will be seen that there is provided a step-by-step positioning device which eliminates the necessity of providing a homing relay and in which homing is effected by a very simple and readily adjustable time delay mechanism. Further, the switch sections controlled by the device can operate through one step only at a time, thus eliminating any "galloping" tendency.

It will be understood, of course, that the present disclosure is not intended to limit the invention, which is capable of further embodiments or modifications, particularly in respect to the structural details. Such modifications are to be deemed within the scope of the invention.

I claim:

1. In a step-by-step positioning device, a movable element having a home position arranged for movement to successive operating positions, means for effecting step-by-step movement of said element to its successive positions in response to successive control impulses, means for urging said element to its home position, means for maintaining said element in each position to which it is moved, means responsive to cessation of an impulse for rendering said maintaining means ineffective, and frictional time-delay means comprising a drum and cable device for retarding the operation of said last-named means for a period sufficient to permit stepping of said element in response to a subsequent control impulse.

2. In a step-by-step positioning device, a movable element having a home position arranged for step-by-step movement to successive operating positions, means for urging said element to its home position, normally inoperative means for maintaining said element in each operating position, means responsive to successive control impulses for stepping said element and for rendering said maintaining means effective, means for restoring said last-named means to normal position, and frictional time-delay means comprising a drum and cable device for retarding the action of said restoring means to thus delay homing of said element for a predetermined period following an impulse.

3. In a step-by-step positioning device, a rotatable element having a home position and a plurality of successive operating positions, means urging said element to its home position, means including a ratchet and a spring-biased holding pawl for maintaining said element in its operating positions, means normally holding said pawl against the action of its spring out of engagement with said ratchet, stepping means including a pawl arranged cooperatively with said ratchet for stepping said element to its operating positions, means responsive to successive control impulses for actuating said stepping means, means operable by said stepping means for rendering the holding means for said holding pawl

inoperative, thereby causing said holding pawl to engage said ratchet, means for restoring said pawl-holding means to normal position, and frictional time-delay means comprising a drum and cable device for retarding the action of said restoring means to thus delay homing of said element for a predetermined period following an impulse.

4. In a step-by-step positioning device, a rotatable element having a home position and a plurality of successive operating positions, means urging said element to its home position, a ratchet connected to said element, a stepping pawl for stepping said ratchet, a holding pawl arranged to engage said ratchet to maintain said element in its operating positions, means urging said holding pawl into engagement with said ratchet, spring-biased means for maintaining said holding pawl normally out of engagement with said ratchet, means operable by the actuation of said stepping pawl for rendering said spring-biased means ineffective, whereby said holding pawl is caused to engage said ratchet, a stationary drum, a cord connected to said spring-biased means and encircling said drum, and a spring arranged to take up the slack of said cord, whereby the return of said spring-biased means to normal position is delayed for a predetermined interval by the frictional drag of said cord over said drum.

5. In a step-by-step positioning device, a rotatable ratchet wheel, a stepping pawl adapted to engage and step said ratchet wheel, a pivoted holding pawl arranged cooperatively with said ratchet wheel, a spring arranged to urge said holding pawl into engagement with said ratchet, a pivoted member engaging said holding pawl and adapted to disengage the holding pawl from the ratchet wheel, a second spring connected to said member and adapted to move the same to its effective pawl-disengaging position, an actuator on said member engageable by said stepping pawl to move said member to ineffective position against the action of said second spring, thereby permitting said holding pawl to engage said ratchet wheel under the influence of said first spring, and means for delaying the return of said member to its effective position under the influence of said second spring following the stepping pawl's release of said actuator.

6. In a step-by-step positioning device, a rotatable ratchet wheel, a stepping pawl adapted to engage and step said ratchet wheel, a pivoted holding pawl arranged cooperatively with said ratchet wheel, a spring arranged to urge said holding pawl into engagement with said ratchet, a pivoted member engaging said holding pawl and adapted to disengage the holding pawl from the ratchet wheel, a second spring connected to said member and adapted to move the same to its effective pawl-disengaging position, an actuator on said member engageable by said stepping pawl to move said member to ineffective position against the action of said second spring, thereby permitting said holding pawl to engage said ratchet wheel under the influence of said first spring, a stationary drum, a flexible cord in opposed relation to said second spring and wound about said drum, and a third spring connected to said cord so as to take up the slack thereof, whereby to delay the return of said member to its effective position under the influence of said second spring following the stepping pawl's release of said actuator.

7. In combination, a pivotally mounted member, a first spring means continuously urging said

member to a predetermined position, a stationary drum, a second spring means, a flexible cord attached to said member and wound about said drum, the free end of the cord being secured to said second spring means to thereby continuously maintain said cord under tension and in frictional engagement with said drum, and means for displacing said pivotally mounted member

from said predetermined position and then releasing the same, said first spring means being constructed and arranged to return said member to said predetermined position at a rate determined by the friction between said cord and said drum.

5 GERALD J. BARRY.
